UNITED STATES PATENT OFFICE.

ROBERT CLIFTON KNIGHT, OF PINNER, AND HUGH DUNFORD SMITH, OF NEWCASTLE-UPON-TYNE, ENGLAND.

MEANS FOR SEPARATING LIQUIDS OF DIFFERENT SPECIFIC GRAVITIES.

Application filed February 29, 1924. Serial No. 696,067.

To all whom it may concern:
Be it known that we, ROBERT CLIFTON KNIGHT, of "Lewdon", West End Avenue, Pinne, in the county of Middlesex, England, and HUGH DUNFORD SMITH, of 7 Side, in the city and county of Newcastle-upon-Tyne, England, both subjects of the King of Great Britain and Ireland, have invented certain new and useful Improved Means for Separating Liquids of Different Specific Gravities, of which the following is a specification.

This invention relates to apparatus for separating liquids of different specific gravities of the type in which the intermingled liquids are passed into a vertically or diagonally disposed U-shaped or two legged conduit (or a conduit approximately of that shape), the lighter liquid remaining in one leg and the heavier liquid passing down the tube around the bend and rising up the other leg, an outlet being provided in each leg for the separated liquids.

In apparatus of this type as hitherto constructed the mixture has been placed under pressure the heavier liquid being drawn off at a higher level than the lighter liquid and the vessel has consequently been closed at the end from which the lighter liquid has been drawn; further, air has been allowed to pass off with the lighter liquid.

The object of this invention is to provide improved apparatus of this type.

Apparatus made in accordance with this invention is characterized in that the intermingled liquids are passed into one leg of the U-shaped conduit at or near the top, the said leg being open to the atmosphere and in that the lighter liquid is drawn off at a higher level than the heavier liquid and further characterized in that the leg of the conduit is sufficiently deep to allow the lighter liquid to ascend against the downward flow of the incoming mixture.

According to this invention we may also provide means for varying the height of the working level of liquid in the U-shaped conduit and we may also provide means for regulating the height of the inflow and/or outflow of the separated liquids. The separated liquids may be caused to pass through a scrubber or other suitable filter.

Means may be provided for drawing off one or both of the separated liquids.

Referring to the drawing filed herewith,

which shows one form of apparatus intended for separating oil and water made in accordance with this invention:

The apparatus comprises a U-shaped conduit consisting of two legs *a* and *b*. The leg *a* is provided with an inlet *c* for the intermingled liquids, that is to say, the oily water, and is also provided with an oil overflow pipe *d*. Between the inlet pipe *c* and the overflow pipe *d* is a diaphragm plate *e* the purpose of which will be hereinafter described. A vent *f* is disposed on the top of the leg *a*. The upper portion of the leg *b* terminates in a bell mouth *g* and is disposed in an observation trap *h*. The bell mouth *g* is screwed on to the leg *b* as shown at *g* whereby its height on the leg *b* may be adjusted.

Surrounding the outlet of the leg *b* is a wire gauze scrubber *j* and in the wall of the trap *h* is an outlet *k* for the separated water which has to pass underneath a baffle *m* before reaching the outlet. A steam heating coil *n* is provided in the tube *a* to render the oil less viscous and to assist in the separation of water from the oil. In the bottom of the U-shaped conduit is a trap *o* for the purpose of drawing off any sludge or solid matter which may settle and a drain cock *p* is fitted for emptying the apparatus.

Adjacent the oil outflow are fitted a series of draw off cocks *r*.

In operation the legs *a* and *b* and also the trap *h* are filled with the heavier liquid, which in this case is water, and the level is shown approximately by the dotted line *Y-Y*.

When starting the apparatus it has been found desirable in practice to form a layer of oil on the oil overflow side of the diaphragm plate in the leg *a* as water is thereby prevented from passing through the oil overflow pipe and the presence of a column of oil has been found to assist in effecting the separation of the intermingled liquids.

The intermingled oil and water is fed into the leg *a* through the pipe *c* and travels downwards, the plate *e* serving to prevent the intermingled liquids approaching the oil overflow pipe *d* and to deflect the upward rising oil which has been separated towards the said overflow pipe. The plate *e* also serves to restrict the superficial area of the separated oil and prevents disturbance of the

2
accumulated oil by the inflowing mixture. As the intermingled liquids flow downwards the oil is separated and rises to the surface of the water in the leg *a* and passes out by 5 the overflow pipe *d* while the water passes on around the bend at the bottom of the conduit and travels up the leg *b* where it flows over the edge of the bell shaped mouth *g* into the trap *h*. This water passes through 10 the wire gauze scrubber *j* and underneath the baffle *m* to the outlet *k*. The working levels in the leg *a* and trap *h* are shown approximately by the dotted line *X*—*X* and *Y*—*Y* respectively.

15 Oil may be drawn off at one of the cocks *r r* according to the thickness of the layer collected.

It has been found desirable in practice to make the leg *a* larger in diameter than the 20 leg *b* and moreover to carry the larger area around the bottom of the conduit and for a short distance up the leg *b*, the object being to maintain a slow rate of flow of the liquid round the bottom of the conduit and to reduce 25 turbulence.

It is of the greatest importance that the legs of the U-shaped conduit be of adequate depth as the greater the depth the greater the efficiency of separation. With a conduit 30 of suitable depth the turbulence caused by the incoming liquid is minimized and a reduction in turbulence increases the efficiency of the separation.

What we claim and desire to secure by 35 Letters Patent is:

1. Apparatus for separating liquids of different specific gravities comprising a substantially U-shaped tube, one leg of said tube being of larger cross-sectional area than the 40 other and the bend being of substantially the same cross-sectional area as that of the larger leg, said larger leg having an inlet and an outlet thereto, said inlet being at the top of the leg and the outlet distanced from the top, said smaller leg having an outlet at 45 the top thereof, and a baffle positioned in said larger leg between the inlet and the outlet thereof.

2. Apparatus for separating liquids of 50 different specific gravities comprising a substantially U-shaped tube having legs of different cross-sectional areas, the bend of said tube merging into the said legs having a cross-sectional area substantially the same as 55 that of the larger leg, said larger leg having

an inlet at the top thereof, and an outlet positioned near the top thereof, an outlet at the top of said smaller leg, and a baffle positioned in said large leg between the inlet and the outlet, said baffle extending below 60 the outlet.

3. An apparatus for separating liquids of different specific gravities as set forth in claim 2, further characterized by a heater positioned in proximity to the outlet of 65 said larger leg, and extending above the lower end of the baffle.

4. An apparatus for separating liquids of different specific gravities as set forth in claim 2, further characterized by a heater positioned in proximity to the outlet of 70 said larger leg and extending above the lower end of the baffle, and a plurality of vertically arranged cut-off cocks on the larger leg below said outlet thereof and positioned on the out- 75 let side of said baffle.

5. Apparatus for separating liquids of different specific gravities comprising a U-shaped tube having legs of different cross-sectional areas, the bend of said tube merging into the said legs having a cross-sectional area substantially the same as that of the larger leg, said larger leg having an inlet at the top thereof, and an outlet positioned near the top thereof, an adjustable outlet at 80 the top of said smaller leg, a baffle positioned in said larger leg between the inlet and the outlet, said baffle extending below the outlet, and a heater positioned in proximity to the outlet of said larger leg. 90

6. Apparatus for separating liquids of different specific gravities comprising a U-shaped tube having legs of different cross-sectional areas, the smaller leg being at least twice as long as the horizontal width of the 95 larger leg, the bend of said tube merging into the said legs having a cross-sectional area substantially the same as that of the larger leg, said larger leg having an inlet thereto at the top thereof, and an outlet positioned near the top thereof, an adjustable outlet at the top of said smaller leg, and a baffle positioned in said larger leg between the inlet and the outlet, said baffle extending below the outlet. 100

In testimony whereof, we affix our signatures.

ROBERT CLIFTON KNIGHT.
HUGH DUNFORD SMITH.
